(Model.)

G. A. MILLER.

WASHING MACHINE.

No. 399,425.

Patented Mar. 12, 1889.

UNITED STATES PATENT OFFICE.

GUSTAVUS ADOLPHUS MILLER, OF BUTLER, PENNSYLVANIA.

WASHING-MACHINE.

SPECIFICATION forming part of Letters Patent No. 399,425, dated March 12, 1889.

Application filed October 22, 1888. Serial No. 288,733. (Model.)

To all whom it may concern:

Be it known that I, GUSTAVUS ADOLPHUS MILLER, a citizen of the United States, residing at Butler, in the county of Butler and State of Pennsylvania, have invented new and useful Improvements in Washing-Machines, of which the following is a specification.

My invention relates to improvements in washing-machines; and it consists in certain novel features hereinafter described and claimed.

In the accompanying drawings, Figure 1 is a perspective view of a washing-machine provided with my improvements. Fig. 2 is a central vertical transverse section of the same. Fig. 3 is a central vertical longitudinal section.

Referring to the drawings by letter, A designates the tub or suds-box of my improved machine, having a semicircular side and a curved bottom, as shown, and supported by the legs B, as will be readily understood. Upon the top of the suds-box I provide the rectangular steam-chest C, provided on its inner faces at its upper end with the cleats D, upon which the lid E rests and slides.

F designates a transverse strip secured to the top of the steam-chest, at one end of the same, and projecting slightly inward over the side thereof, so as to receive the edge of the lid and hold it in place when it is drawn out to close the opening in the top of the steam-chest.

G designates a board or plate secured to the top of the steam-chest and covering about half of the same and provided on its upper side with the rib H, forming a wringer-rail, to which the clothes-wringer may be clamped.

I designates the beater, consisting of a metallic bar bent reversely on itself to form the parallel branches or arms J, and having its ends journaled in suitable bearings in the sides of the suds-box, one of said ends being extended beyond the suds-box and provided with an operating crank-handle, J', as shown.

L designates a series of transverse rubbing-pins, which are secured between the lower edges of the sides of the suds-box, a short distance above the bottom of the same, as clearly shown.

In operation the clothes are placed in the suds-box, together with the boiling water and soap or other cleansing material, the lid closed, and the beater then rapidly rotated. It will be observed from Fig. 2 of the drawings that the beater is very nearly equal in length to the diameter of the suds-box, so that the rotation of the same will cause a thorough agitation of the clothes and will carry them around through the water and up out of the same through the steam which will collect in the steam-chest or upper portion of the machine, consequently effecting a thorough and rapid cleansing of the clothes. When the clothes have been cleaned, a wringer is clamped to the wringer-rail, the lid shoved back, and the clothes drawn from the suds-box and passed through the wringer, as will be readily understood.

It will be observed that I have provided a very simple machine. The agitator or beater being formed of a single metallic rod and journaled in the suds-box, without the employment of the usual shafts, leaves the interior of the suds-box free from all obstructions, so as to obviate the liability of tearing the clothes, as has been usual heretofore. The peculiar construction of the agitator, furthermore, renders it very light and at the same time very strong, so that the machine can be easily operated to agitate the clothes.

Having thus described my invention, what I claim, and desire to secure by Letters Patent, is—

As an improvement in washing-machines, the combination of the tub B, the steam-chest C secured thereon, the sliding lid in the upper portion of the steam-chest, and the rotary beater consisting of a metallic bar having its ends journaled in the sides of the tub and its intermediate portion bent reflexly to form a series of arms, which extend on opposite sides of the axis of the beater, as specified.

In testimony that I claim the foregoing as my own I have hereto affixed my signature in presence of two witnesses.

GUSTAVUS ADOLPHUS MILLER.

Witnesses:

A. E. REILEY,
ANDREW MILLER, Jr.
